COLLECTOR

Henry C. French, Elm Grove, Wis., assignor to
Arnold Dryer Co., Milwaukee, Wis., a corpora-
tion of Wisconsin

Application June 9, 1945, Serial No. 598,601. 4 Claims. (Cl. 183—83)

1

This invention relates to improvements in collectors, and more particularly to a collector for association with a hammermill.

Collectors of the "cyclone separator" type are customarily used in connection with hammermills or like mechanisms for the purpose of separating and collecting solid particles of a predetermined desired size from the undesirable lighter and more minute material with which they are entrained in the air currents. In conventional hammermill collectors a certain proportion of the desired larger particles of the material are lost through being exhausted to the atmosphere with the discharged air. In an effort to save or recapture some of the heavier material operated on in conventional collectors which might be exhausted with the discharged air, it has heretofore been proposed to have the inner end of a skimmer pipe open into an upper portion of the collector body to skim off certain of the heavier material entrained in the discharging air, which heavier material is thrown out centrifugally and is skimmed out of the rising air eddies by the skimmer pipe, which then returns the material thus salvaged to the hammermill for reprocessing therein and subsequent recirculation back to the collector. An arrangement of the aforementioned type necessitates an extremely long skimmer pipe extending between the upper portion of the collector body and the hammermill, and increases the cost of the apparatus.

With the foregoing in mind, it is, therefore, a primary object of the present invention to provide a hammermill collector which will prevent the undesirable exhaust to the atmosphere of sizable particles of material which should not be wasted by the utilization of simple, compact means associated directly with the collector whereby desirable heavy material in the air seeking to discharge from the collector is skimmed from said discharging air and is returned via a short return or skimmer pipe into a lower portion of the collector where it commingles with the originally separated heavy material and gravitates therewith to the collection end of the collector.

A further object of the invention is to provide a hammermill collector having simple, inexpensive and compact means associated therewith for salvaging desirable heavy material which might otherwise be wasted.

A further object of the invention is to provide a hammermill collector having an internal skirt member therein arranged relative to the inlet end of a skimmer or return pipe so that desirable material salvaged from the upper end of the col-

lector body is held above and stabilized in a position to facilitate its discharge into the body of the collector.

Other objects and features of the invention will be apparent from the following description of the preferred embodiment, reference being had to the accompanying drawings.

It is to be understood that the invention is not limited to the specific embodiment shown, but is intended to cover all improvements and equivalents which may be made within the spirit and scope of the invention as defined in the claims.

Referring now more particularly to the drawings, Fig. 1 is a side view of the improved collector

with the inlet pipe being shown in section; Fig. 2 is a vertical sectional view taken on line 2—2 of Fig. 1; and Fig. 3 is a plan view of the collector.

Referring now more particularly to the drawings, it will appear that the collector comprises a hollow body member 5 which is generally in the form of an inverted cone, with the enlarged upper end portion 5' being of cylindrical formation.

The top of the cylindrical portion of the body has centrally mounted therein so as to extend substantially downwardly within the upper interior portion of the collector body, an air vortex sleeve 6, open at its lower end. The upper end portion of said sleeve 6 projects beyond the top closure portion 7 of the collector body with the inner periphery of the closure portion 7 being welded or otherwise secured to outer peripheral portions of the sleeve 6. The upper end of the sleeve 6 is formed with a collar-like cover 8, in the central opening of which is secured the upper end of a skimmer tube 9 which depends a substantial distance into the upper end of the sleeve 6, being of substantially less diameter than the sleeve 6 and spaced annularly therefrom.

Spaced upwardly, outwardly directed straps 10 have their lower end portions secured to upper peripheral portions of the skimmer tube 9 and the upper flanged extremities of the straps 10 are secured to and carry a top cap 11. The air vortex with entrained light and unusable material discharges from the collector through the open upper end of the skimmer tube 9, passing to the atmosphere between the straps 10 and below the cap 11, and via further air inlets and outlets.

Within the conical portion 5 of the collector,

intermediate the ends thereof, is secured a hollow skirt member 12 which is in the form of the frustum of an inverted cone, being open at both ends and having its enlarged upper end in contact with and secured to inner wall portions of the collector body 5. The inclination of the downwardly directed side wall portions of the skirting 12 is greater than that of the adjacent side wall portions of the collector body 5 so that below the connection between the skirting 12 and the body 5 there is gradually enlarging space between adjacent wall portions of said members 12 and 5. Entering the wall of the collector body portion 5 adjacent said space between the collector body wall and the skirting is the discharge end of a return pipe 13, said open end being arranged to discharge into the collector body tangentially. The major portion of the return pipe 13 is mounted vertically adjacent the exterior portion of the collector body, with the upper end of the pipe 13 being turned inwardly and opening into the upper end of the sleeve 6 tangentially. The upper inlet end of the return pipe 13 is designated by the numeral 14 in the drawing, while the lower discharge end of the return pipe 13 is designated by the numeral 15.

An elongated inlet pipe is designated by the numeral 16 and its upper end opens tangentially into the upper end of the cylindrical portion 5' of the collector body. In practice the pipe 16 extends to and is connected with a fan or blower (not shown) which is in association with a hammermill (not shown) so as to force material which has been comminuted or reduced in the hammermill outwardly through the pipe 16. Hence, via the pipe 16, bulk material of a reduced or comminuted character, such as meal, fodder or the like, is introduced in a continuous, forced stream into the enlarged upper end of the collector body.

In the operation of the improved collector, a typical function of which is to collect particles of heavy meal which has been comminuted or reduced in a hammermill, a continuous stream of the material is forcefully introduced tangentially into the enlarged upper end portion 5' of the collector body. This material initially circulates in a downwardly progressing spiral path between the exterior of the sleeve 6 and the interior of the collector body portions 5' and 5. The tendency of the whirling material is to stay toward the inner wall of the collector body, but as the collector body tapers inwardly downwardly, the whirling material is eventually forced inwardly and meets the central vortex. Most of the heavy meal particles, which it is desired to collect, nevertheless gravitate downwardly counter to the current of the inner air vortex and are discharged through the reduced lower open end 17 of the collector body 5, the desired particles of the bulk material being caught in suitable containers. Not all of the heavy meal entering the upper end of the collector body gravitates as described to the lower discharge end of the collector. Some of it remains entrained in the whirling air and the function of the present improvement is to salvage and return to the discharge end of the collector such particles of heavy meal or other bulk material which might otherwise be exhausted to the atmosphere with the discharged air in the central vortex and be wasted. In the accomplishment of this purpose, as the whirling air with some heavy meal particles remaining therein, is constricted, it is drawn into the central air vortex in the collector body and is then drawn upwardly into the vortex

sleeve 6, the air and entrained material moving spirally upwardly with the heavy meal particles remaining therein being thrown out centrifugally adjacent the inner surface of the sleeve 6. This action continues throughout the vertical extent of the sleeve 6 and the heavy meal, which is thrown out centrifugally, is sucked out of the air vortex by the down current in the return pipe 13 whose open upper end 14 enters the upper end of the sleeve 6 tangentially. The whirling air, with lighter material therein which is not to be recovered, is constricted into the skimmer tube 9 and is discharged out of the collector to the atmosphere. The skimmed or salvaged meal or bulk material flows downwardly through the pipe 13 and is re-introduced into an intermediate portion of the collector body 5 in the annular space exteriorly of the skirting 12. This material is introduced into the collector body in a direction so as to whirl and the stream merges with the whirling stream of gravitating heavy meal which was initially separated. The reintroduced skimmed meal or material comes into the collector below the vortex area and is prevented from being influenced by the vortex because of the skirting 7. Thus, the recirculated salvaged bulk material is permitted to gravitate to the discharge end of the collector with the main descending stream of the heavy material and is recovered from the collector at the lower outlet end thereof.

The improved collector, incorporating the salvaging or skimming feature, requires a minimum of parts and additions over that required in a standard collector, is simple and compact and efficient in operation, and is well adapted for the purposes described.

What is claimed as the invention is:

1. In combination with a hollow collector body in the form of an inverted cone and having an exhaust centrally in its upper end, a material delivery pipe opening tangentially into an upper side portion of the body, and a material discharge opening in the lower end of the body, an annular skirt member mounted within the body intermediate the ends thereof with major portions of the skirt member being spaced from the body wall, the upper annular end of the space between the body and skirt being closed relative to the body cavity there above, a sleeve communicating with the air exhaust and depending from the top of the body and spaced from the side walls thereof and spaced from the upper end of said skirt, and a material return pipe in communication with and extending from said sleeve to an intermediate portion of the body and having its discharge end opening into the body in the space between the skirt member and the body wall.

2. In combination with a hollow, downwardly tapered collector body having a centrally located, constricted air exhaust in its upper end, a material delivery pipe opening tangentially into an upper side portion of the body, and a material discharge opening in the lower end of the body, an annular, downwardly tapered skirt member mounted within the body intermediate the ends thereof and having its upper periphery secured to inner wall portions of the body, the taper of the skirt member being in the same direction as but greater than the taper of the body to provide an annular, downwardly widening space therebetween which is closed relative to the body space thereabove, a sleeve of less diameter than the upper portion of the body depending centrally thereinto and substantially spaced from the upper end of the skirt, a skimmer tube com-

municating with the air exhaust and depending centrally into said sleeve, said skimmer tube being of smaller diameter and of less length than said sleeve, and a down flow material return pipe extending from an upper portion of the sleeve to an intermediate portion of the body and having its discharge end opening tangentially into the body in the space between the skirt member and the body wall.

3. A collector, comprising a hollow body generally in the form of an inverted cone with a bulk material discharge opening in its lower end, a material delivery pipe opening tangentially into an upper side wall portion of the body, a cylindrical sleeve of less diameter than the upper portion of the body depending concentrically thereto, the open lower end of the sleeve being within the zone of an upwardly rising air vortex, a cylindrical skimmer tube of less diameter than the sleeve and depending concentrically thereto and having its lower end terminating short of the lower end of the sleeve, the top of said tube being formed with an air exhaust, an annular, downwardly tapered skirt mounted within the body in sealing relation to the inner wall of the body and spacedly below the lower end of the sleeve, the taper of the skirt being greater than the taper of the body to provide an annular, downwardly widening space therebetween whose upper end is closed relative to the body opening thereabove, and a down flow material salvaging pipe mounted exteriorly of the body and having its upper end opening tangentially into the sleeve and having its lower end opening tangentially into the body in the space between the skirt and body wall and substantially below the zone of the upwardly rising air vortex within the body.

4. In combination with a hollow, hammermill collector body substantially in the form of an inverted cone and having an exhaust centrally in its upper end, a bulk material delivery pipe opening tangentially into an upper side portion of the body, and a bulk material discharge opening in the lower end of the body, a sleeve communicating with the air exhaust and depending from the top of the body and entirely spaced concentrically from the side walls thereof, the lower end of the sleeve being within the zone of an upwardly rising air vortex produced within a portion of the body, an annular imperforate, tapered skirt having the upper end secured to and engaging an annular inner wall portion of the body, the taper of the skirt being in the same direction as but greater than the taper of the body to provide an annular, downwardly widening space therebetween baffled relative to the rising air vortex zone in the body there above, and a bulk material salvage return pipe in communication with and extending from said sleeve to an intermediate portion of the body and having its discharge end opening tangentially into the body in the annular space between the skirt and the body wall, the arrangement of the discharge end of the return pipe being such as to cause the discharged material to whirl in the space between the skirt and body in a direction to gravitate and ultimately commingle with the stream of bulk material descending in the lower portion of the body toward the discharge opening.
